UNITED STATES PATENT OFFICE.

JACKSON D. COMSTOCK, OF CHESTER, WEST VIRGINIA.

DESIGN FOR AN AUTOMOBILE TIRE CASING.

Application filed July 3, 1922. Serial No. 2,956. Term of patent 14 years.

To all whom it may concern:

Be it known that I, JACKSON D. COMSTOCK, a citizen of the United States, residing at Chester, in the county of Hancock and State of West Virginia, have invented a new, original, and ornamental Design for Automobile Tire Casings, of which the following is a specification, reference being had to the accompanying drawings, forming a part hereof.

Fig. 1 is a perspective view of a tire casing showing my design; Fig. 2 is a side elevation of the same; and Fig. 3 is a transverse radial section of the casing showing the relative disposition of the various ribs.

I claim:

The ornamental design for an automobile tire casing as shown.

JACKSON D. COMSTOCK.
